UNITED STATES PATENT OFFICE.

HARRY L. RODERICK, OF OROVILLE, AND LABANNA T. McCUTCHEON, OF SANTA CRUZ, CALIFORNIA.

MEANS FOR CONTROLLING DOORS AND STEPS OF CARS.

1,057,010.

Specification of Letters Patent.

Patented Mar. 25, 1913.

Application filed January 14, 1913. Serial No. 742,048.

To all whom it may concern:

Be it known that we, HARRY L. RODERICK and LABANNA T. McCUTCHEON, citizens of the United States, residing, respectively, 5 at Oroville, in the county of Butte, and Santa Cruz, in the county of Santa Cruz, State of California, have invented new and useful Improvements in Means for Controlling Doors and Steps of Cars, of which the following is a specification.

Our invention relates to improvements in the means for opening the doors and for projecting the steps of railway cars, and the object of our invention is to provide means 15 whereby such operations may be controlled by the stoppage and starting of the car.

In the accompanying drawing, Figure 1 is a side view of a railway car, certain parts not material to our invention being omitted; 20 Fig. 2 is an enlarged transverse section of a valve and its casing; Fig. 3 is an enlarged rear view of controlling means; Fig. 4 is an end view of the car; Fig. 5 is an enlarged plan view of mechanism for operating the 25 steps and part of the mechanism for operating the doors.

Referring to the drawing, 1 indicates the body of a railway car. Rotated by one of the wheel axles 2 of said car is a bevel gear 3 meshing with a bevel gear 4 on a vertical shaft 6, which carries a centrifugal governor 7, connected by a link 8 to the crank arm 9 of a rotary valve 10 rotatable in a valve casing 11. Said valve, illustrated in section in 30 Fig. 2, is here shown in its position when the car is at rest, in which position one inlet branch 12 of a transverse conduit 13 communicates with a port 14 in the valve casing 11 connected by a pipe 16 with a source of compressed air, not here shown. The other inlet branch 17 of said conduit is at this time closed, and the outlet end of said conduit 35 communicates with a port 18, from which a pipe 19 leads to one end of a cylinder 21. From the other end of said cylinder a pipe 22 leads to a port 23 in the valve casing 11, which port 23 at this time communicates with a conduit 24 in said valve, communicating at the other end with a port 26 in the 40 valve casing leading to the atmosphere. In this position of the valve, therefore, the piston in the cylinder 21 is pressed from left to right. When the car is in motion the centrifugal governor 7 rises, and when the car 45 has obtained a sufficient speed, said gov-

ernor has turned the valve 10 through such an angle that the branch 17 of the conduit 13 communicates with the port 14, while the outer end of said conduit 13 communicates with the port 23. At the same time the port 18 50 communicates by means of a conduit 27 in the valve with a port 28 in the valve casing leading to the atmosphere. It will readily be seen that, under these conditions, the left hand end of the cylinder is open to 55 exhaust while the right hand end of the cylinder communicates with the source of supply of compressed air, and the piston in the cylinder moves from right to left. Said piston is connected to two piston rods 31, 32, 60 passing through stuffing boxes 33 in the respective ends of the cylinder and passing through guides 34 toward the ends of the car. The outer end of each piston rod is connected (Fig. 5) to a link 36, which is 65 connected to the outer end of a crank arm 37 secured to a sleeve 38 loose on a transverse shaft 39, the ends of which are journaled in bearings 41 and connected to arms 42, the outer ends of which are connected to 70 links 43 which are connected to the slidable doors 44 of the car. Said sleeve is formed with a clutch member 46 which is adapted to engage a clutch member 47 slidably keyed to the transverse shaft 39, and connected to 75 a yoke 48 operated by a lever 49, an arm of which is actuated by a spring-repressed stem 51 extending above the floor of the car and arranged to be depressed by the foot of the conductor or motorman. Below the fixed 80 steps 52 at each end of the car are movable steps 53 slidable in guideways 54 and connected to links 56, which are connected to the outer ends of arms 57 on a vertical shaft 58 on which is a loose sleeve 60 having an 85 arm 59 connected to a link 61 also connected to the outer end of the corresponding piston rod. Said sleeve 60 is adapted to be engaged by a clutch 62 depressed by a lever 63 operated by a spring-repressed stem 64. 90

The mode of operation of the apparatus is as follows: When the conductor or motorman wishes to open the doors 44 or to project the step 53 upon the arrival of the car at any desired station, he depresses the stem 105 51 or 64 and thereby brings the corresponding transverse shaft into operative relation with the sleeve. Then, when the car stops, the valve 10 is turned by the governor so that compressed air is admitted to the 110

proper end of the cylinder to turn both transverse shafts and open the gates or project the lower steps. When the car is again started, if the proper foot stem is depressed, 5 the compressed air will operate the piston to move the transverse shaft in the opposite direction, and close the gates or withdraw the steps.

We claim:—

- 10 In combination with a shaft rotated in the movement of a car, a centrifugal governor controlled by said shaft, a lever controlled by said centrifugal governor, a valve controlled by said lever, a source of supply 15 of pressure fluid controlled by said valve, a cylinder into which said pressure fluid is supplied through said valve, piston rods extending toward the opposite ends of the

cars respectively and moved by said pressure fluid, movable doors and steps at opposite ends of the car, and operative connections between the piston rods and said doors and steps, whereby, when said car is stopped, pressure fluid is applied in the direction to open said doors and project said 25 steps, and when the car is in motion pressure fluid is applied in the opposite direction.

In testimony whereof we have hereunto set our hands in the presence of two subscribing witnesses.

HARRY L. RODERICK.
LABANNA T. McCUTCHEON.
